WINDOW

Charles L. Franklin, Brooklyn, N. Y.

Application September 11, 1933, Serial No. 689,028

7 Claims. (Cl. 20—40)

This invention relates to a window which is designed and adapted preferably for dwellings, detached houses, and other buildings.

Some of the uses, advantages, and structural features of the window of the present invention are as follows: it makes possible the obtainment of the desired ventilation while preventing vision from the outside, yet permitting vision from the inside thereof; it provides an assembly of interconnected sashes movable with respect to each other and with respect to a frame, to close a corresponding portion of the frame opening, or to constitute in conjunction with a suitable extension or platform, a bay structure to give ventilation while serving as a guard to prevent children from falling out of the window, and also as a means to receive goods from tradesmen and others without requiring entry of such tradesmen and others.

With the foregoing and other ends in view, the invention resides in the features as hereinafter described and claimed and as illustrated in the accompanying drawings, in which

Figure 1 is a vertical section of a window embodying the features of the invention, the section being taken on the line 1—1 of Fig. 2;

Fig. 2 is a section taken on the line 2—2 of Fig. 1;

Fig. 3 is a similar view to Fig. 2, but showing the platform down and the sash assembly in open formation to provide one type of bay structure;

Fig. 4 is a view similar to Fig. 3, but showing the sash assembly arranged to provide another closed type of bay structure;

Fig. 5 is a fragmentary detail view;

Fig. 6 is a perspective view of the assembly of sashes in open formation looking at the same from the inside;

Fig. 7 is an enlarged detail section.

In the illustrated embodiment of the invention, there is shown a window frame 10, which may be of suitable construction, either of metal or wood, and which will include a sill 11, a weather stop 12 on the sill 11, and weather stops 13 and 14 on each of the side stiles 15 of the frame 10. An upper sash 16 is arranged in the frame 10 and has up and down movement guided by the stops 13 and 14. A recess 17 in the head rail of the frame permits the sash 16 to move upwardly from its down position. The sash 16 has a pair of sliding latches 18 on the bottom rail thereof, each of which is receivable in upper and lower holes 19 and 20, respectively, in each stop 14. The latches 18 when received in the holes 20, secure the sash 16 in its down position, and when said latches 18 are received in the holes 19, hold the sash 16 in an up position, as shown in Fig. 5, for a purpose to appear. The bottom rail of the sash 16 has a weather strip 21 on the outside thereof and depending below the bottom surface thereof.

In accordance with the invention, use is made

of an assembly of sashes 22, 23, 24 and 25. In the present instance, one side of the sash 22 is mounted to swing inwardly and outwardly on a vertical axis provided by a hinge connection 26 connected with the outside face of the sash 22 and the inside of the stop 13 on the left-hand stile 15 of the frame 10, looking at the same from the inside. The right-hand side of the sash 22 is connected with the left-hand side of the sash 23 by a hinge connection 27, so that the left-hand side of the sash 23 will abut the right-hand side of the sash 22 and be disposed in the plane of the sash 22 and also to be moved to different angular positions with respect thereto. The right-hand side of the sash 23 is connected with the left-hand side of the sash 24 by a hinge connection 28 so that the left-hand side of the sash 24 may abut the right-hand side of the sash 23 to be disposed in the same plane with the latter, as shown in Fig. 3, and that the sash 24 may be disposed at an angle with respect to the sash 23, as shown in Fig. 4, and, also, that the sash 24 may be disposed side by side with respect to the sash 23, as shown in Fig. 2. The sash 22 is rabbed on the inside, as at 29, to receive the sash 25, which is connected with the sash 22 by a hinge connection 30, so that the sash 25 may be swung to an open position with respect to the sash 22 and also to be disposed flush within the frame of the sash 22. The sash 22 has a transparent pane of glass 31, and each of the other sashes 23, 24 and 25, preferably has a translucent pane of glass 32. The sash 25 is held in a closed position by any suitable device, such as a hook 33 on the sash 22, and a staple or eye 34 on the sash 25, which receives the hook 33. The sash 24 has a brace 35 in the form of an angle iron, said brace having one end pivoted, as at 36, to the top rail of the sash, and the other end of the brace has a hole 37 to receive a pin 38 which is also receivable in a staple or eye 39 on the frame 10. The brace 35 may be swung into a position to parallel the top rail of the sash 24 when not in use, to brace the sash 24. In such position the brace 35 will contact with the weather strip 21 when the sash assembly is in its closing position, as shown in Fig. 1. The assembly of sashes in the closing position will be in close formation, and will be disposed wholly within the plane of the frame 10, as shown in Fig. 2. When the brace 35 is pinned to the staple 39, it will hold the assembly of sashes so as to constitute an open bay, as shown in Fig. 3. The sash 24 also has a hinged hasp 40, which is engageable with a staple 41 on the stop 13 of the right-hand stile 15 of the frame 10, looking at the latter from the inside. When the hasp is engaged with the staple 41, the sashes will be in the relationship shown in Fig. 4, forming a closed bay and the sashes may be locked in this formation by

employing a lock (not shown), in conjunction with the staple 41 while the hasp 40 is engaged with the latter. The hasp 40 may be engaged with a staple 42 on the sash 22 when the assembly of sashes is in the closing relation as shown in Fig. 2, and may be locked in this relation by the lock referred to above engaged with the staple 42, when the latter is received in the hasp 40. In swinging the assembly of sashes into the open and close formation, as shown in Figs. 2, 3 and 4, the upper sash 16 will be raised in the recess 17 by releasing the latches 18 from the holes 20 and re-engaging them in the holes 19, as will be understood.

15 In accordance with another feature of the invention, there is provided a platform or grille 43, which is mounted for pivotal movement on a horizontal axis provided by a shaft 44 mounted in bearing brackets 45 on the outside of the building structure. The platform 43 is movable into an up or out-of-the-way vertical position, as shown in full lines, and also into a down or horizontal service position, as shown in dotted lines in Fig. 1. The movement of the platform 43 is effected by the employment of a crank 46 extending outwardly beneath the sill 11 and having a worm 47 on its outer end which meshes with a worm gear 48 on the shaft 44. A suitable casing 49 encloses or houses the worm 47 and gear 48, and also serves to support the outer end of the crank 46. Brackets 50 are employed to support the platform 43 in its horizontal or down position. Each of these brackets is swingable on a vertical axis provided by pivots 51 supported by a bearing 52, the bracket having an arm 53 with which a push-and-pull rod 54 is pivotally connected, as at 55, said rod 54 extending inwardly through the building structure. The brackets 50 may be swung outwardly by pushing on the rods 54 to support the platform 43, and said brackets may be swung to lie against the building by pulling on the rods after the platform 43 has been raised. This platform 43 and the brackets 50 are made movable to out-of-the-way positions merely to provide clearance when that is necessary, in a driveway for instance. If desired, the platform may be fixed in its horizontal position. The platform 43 in its horizontal position constitutes a bottom in conjunction with the assembly of sashes when extended to form the bays. When the assembly of sashes is in the open formation, as shown in Fig. 5, the bay formed will be open, preferably at what would be the rear of the bay so that goods may be received from tradesmen and others who will place the goods on the platform 43. When the assembly of sashes is in the open formation, as shown in Fig. 4, the bay formed will be closed so as to provide the desired ventilation and, at the same time, serve as a guard to prevent children from falling out of the window. The assembly of sashes in the open formation shown in Fig. 4, prevents vision from the outside into the room while furnishing the desired ventilation. The sash 25 may be swung to an open position to permit vision from the inside to the exterior through the transparent pane of glass 31 in the sash 22. The sash 25 when swung to an open position also allows forward vision from the interior when the assembly of sashes is in the formation shown in Fig. 3.

It is to be understood that the assembly of sashes may be unattached so as to be used with a window having sliding sashes. In such case, the lower sash will be raised and the assembly of sashes described used in the manner illustrated.

What is claimed is:

1. In a window, a frame, and an assembly of sashes movable relatively to each other, so that the sashes may be put in close formation for disposition wholly in the plane of the frame to close the opening in a corresponding portion thereof, and also that the sashes may be put in open formation to constitute with said frame a bay window structure. 80
2. In a window, a frame, an assembly of sashes movable relatively to each other, and means connecting the assembly with said frame so that the assembly may swing on a vertical axis, the provision and arrangement being such that the sashes may be put in close formation for disposition wholly in the plane of the frame to close the opening in a corresponding portion thereof, and also that the sashes may be put in open formation to constitute with said frame a bay window structure. 85
3. In a window, a frame, an assembly of sashes movable relatively to each other, and means connecting one side of the assembly with said frame so that the assembly may swing on a vertical axis, the provision and arrangement being such that the sashes may be put in close formation for disposition wholly in the plane of the frame to close the opening in a corresponding portion thereof, and also that the sashes may be put in open formation to constitute with said frame a bay window structure. 90
4. In a window, a frame, and an assembly of hingedly connected sashes, so that the sashes may be put in close formation for disposition wholly in the plane of the frame to close the opening in a corresponding portion thereof, and also that the sashes may be put in open formation to constitute with said frame a bay window structure. 100
5. In a window, a frame, an assembly of sashes movable relatively to each other, means connecting one side of the assembly with said frame so that the assembly may swing on a vertical axis, the provision and arrangement being such that the sashes may be put in close formation for disposition in the frame to close the opening in a corresponding portion thereof, and also that the sashes may be put in open formation to constitute with said frame a bay window structure. 105
6. In a window, a frame, an assembly of sashes movable relatively to each other, means connecting one side of the assembly with said frame so that the assembly may swing on a vertical axis, the provision and arrangement being such that the sashes may be put in close formation for disposition wholly in the plane of the frame to close the opening in a corresponding portion thereof, and also that the sashes may be put in open formation to constitute with said frame a bay window structure, and means to detachably connect the remaining side of the assembly with the frame in spaced relation thereto. 115
7. In a window, a frame, an assembly of sashes movable relatively to each other, so that the sashes may be put in close formation for disposition wholly in the plane of the frame to close the opening in a corresponding portion thereof, and also that the sashes may be put in open formation to constitute with said frame a bay window structure, and means to detachably connect the remaining side of the assembly contiguous to the frame. 120
8. In a window, a frame, an assembly of sashes movable relatively to each other, so that the sashes may be put in close formation for disposition wholly in the plane of the frame to close the opening in a corresponding portion thereof, and also that the sashes may be put in open formation to constitute with said frame a bay window structure, and means to hold the assembly disposed in the frame as aforesaid. 125
9. In a window, a frame, an assembly of sashes movable relatively to each other, so that the sashes may be put in close formation for disposition wholly in the plane of the frame to close the opening in a corresponding portion thereof, and also that the sashes may be put in open formation to constitute with said frame a bay window structure, and means to hold the assembly disposed in the frame as aforesaid. 130
10. In a window, a frame, an assembly of sashes movable relatively to each other, so that the sashes may be put in close formation for disposition wholly in the plane of the frame to close the opening in a corresponding portion thereof, and also that the sashes may be put in open formation to constitute with said frame a bay window structure, and means to hold the assembly disposed in the frame as aforesaid. 135
11. In a window, a frame, an assembly of sashes movable relatively to each other, so that the sashes may be put in close formation for disposition wholly in the plane of the frame to close the opening in a corresponding portion thereof, and also that the sashes may be put in open formation to constitute with said frame a bay window structure, and means to hold the assembly disposed in the frame as aforesaid. 140
12. In a window, a frame, an assembly of sashes movable relatively to each other, so that the sashes may be put in close formation for disposition wholly in the plane of the frame to close the opening in a corresponding portion thereof, and also that the sashes may be put in open formation to constitute with said frame a bay window structure, and means to hold the assembly disposed in the frame as aforesaid. 145
